(57) **CLAIM**

The ornamental design for a moving stage light with light tube, as shown and described.

DESCRIPTION

FIG. 1 is a front perspective view of a moving stage light with light tube showing the new design;

FIG. 2 is a front view thereof;

FIG. 3 is a right-side view thereof;

FIG. 4 is a back view thereof;

FIG. 5 is a left-side view thereof;

FIG. 6 is a top view thereof; and,

FIG. 7 is a bottom view thereof.

The broken lines in the drawing are for the purpose of illustrating unclaimed portions of the moving stage light with light tube and form no part of the claimed design.
